UNITED STATES PATENT OFFICE.

BOYD B. KEITH, OF MANSFIELD, OHIO.

STEP-LADDER.

1,235,696.

Specification of Letters Patent.

Patented Aug. 7, 1917.

Application filed August 21, 1916. Serial No. 116,122.

To all whom it may concern:

Be it known that I, BOYD B. KEITH, a citizen of the United States, residing at Mansfield, in the county of Richland and State 5 of Ohio, have invented a new and useful Step-Ladder, of which the following is a specification.

The device forming the subject matter of this application is a bracing mechanism for 10 a step ladder, to prevent the step ladder from swaying or tilting sidewise.

The invention aims to provide novel means whereby the upper ends of the props are connected with the step ladder in such 15 a way that the props may be swung around against the outer sides of the legs of the ladder.

Another object of the invention is to provide novel means whereby the parts 20 which connect the props with the ladder, will constitute, also, a mechanism for connecting the legs of the ladder pivotally with the top platform of the ladder.

It is within the province of the dis- 25 closure to improve generally and to enhance the utility of devices of that type to which the present invention appertains.

With the above and other objects in view which will appear as the description pro- 30 ceeds, the invention resides in the combination and arrangement of parts and in the details of construction hereinafter described and claimed, it being understood that changes in the precise embodiment of the 35 invention herein disclosed can be made within the scope of what is claimed without departing from the spirit of the invention.

In the accompanying drawings:—

Figure 1 shows in front elevation, a step 40 ladder constructed in accordance with the present invention, the props being in out- standing positions;

Fig. 2 is a side elevation of a step ladder embodying the present invention, the props 45 being swung against the outer faces of the legs of the ladder;

Fig. 3 is a fragmentary horizontal section, showing the means whereby the props are pivotally connected with the platform 50 portion of the ladder; and

Fig. 4 is a view similar to Fig. 3 but illustrating a slight modification in the invention.

The step ladder to which the disclosed 55 invention is applied, may be constructed variously. In the present instance, it is

shown as comprising forward legs 1 connected by treads 2, and rear legs 3, connected by crossed ties 4. The forward legs 1 may be connected with the rear legs 3 by 60 means of folding braces 5. The ladder is shown as comprising a top platform 6 to which the legs 1 and 3 are pivotally connected. The foregoing structure is common in the art, and may be changed without 65 jeopardizing the utility of the invention as hereinafter described.

Fixed to and depending from the top platform 6 are hangers 7. The hangers 7 are of U or trough shape in cross section and embody inner walls 8 and outer walls 9. The upper ends of the legs 1 and 3 lie between 70 the constituent walls 8 and 9 of the hangers 7.

The invention includes U-bolts 10, the 75 arms of which pass through the walls 8 and 9 of the hangers 7 and through the upper ends of the legs 1 and 3. The arms of the U-bolts, therefore, serve as a means whereby by the legs 1 and 3 are pivotally connected 80 with the top platform 6. Nuts 11 may be threaded onto the arms of the U-bolts 10, the nuts 11 engaging the outer faces of the outer walls 9. Nuts 12 may be threaded onto 85 the ends of the arms of the U-bolts 10, the nuts 12 engaging the inner faces of the inner walls 8 of the hangers 7.

The invention includes side props 14 having openings 15 at their upper ends, in 90 which openings the curved portions of the U-bolts 10 are received. The props 14 may be equipped at their lower ends with rubber tips 16, enabling the lower ends of the props to secure a firm hold on the floor. Adjacent 95 their lower ends, the props 15 are provided with slots 17. Threaded or otherwise mounted to rotate in the legs 1 are securing elements which may be angle hooks 18, the angle hooks 18 being adapted to coöperate with the slots 17 in a manner to be described 100 hereinafter.

In practical operation, when the props 14 are in outstanding relation to the legs of the ladder, as delineated in Fig. 4, the ladder will be prevented from swaying or tilting 105 sidewise.

When the occasion for the use of the props 14 has passed, the props may be swung around until they abut against the outer faces of the legs 1, as shown in Fig. 2, the 110 upper ends of the props 14 sliding on the curved portions of the U-bolts 10, because

the upper portions of the props are equipped with the openings 15. When the props 14 lie against the outer sides of the legs 1 of the ladder, the angle hooks 18, which pass 5 through the slots 17, may be rotated, until the extremities of the angle hooks engage the props, and hold the props against the legs 1, in a manner which will be plain from Fig. 2 of the drawings. It is obvious that, 10 if desired, the props 14 may be swung around against the rear legs 3.

It is not necessary that the nuts 11 and 12 be used. In Fig. 4 of the drawings, a slight modification of the invention has been 15 shown. In Fig. 4 of the drawings, numerals previously used have been employed with the suffix "a". In this form of the invention, the U-bolts 10^a are equipped with shoulders 11^a, replacing the nuts 11. In the 20 place of the nuts 12, the ends of the arms of the U-bolts 10^a are riveted down as shown at 12^a, onto the plates 8^a of the hangers.

The construction of the device is such that the ladder can be used on the side of a hill or on uneven ground, without danger of up- 25 setting.

Having thus described the invention, what is claimed is:—

A step ladder including a top; a U-member comprising arms assembled with the top; legs mounted to swing on the arms of the U-member; and a side prop having its upper end mounted to travel on the bend of the U-member, circumferentially of the bend, whereby the prop may be rotated axially and be swung against one leg, into alignment therewith. 30 35

In testimony that I claim the foregoing as my own, I have hereto affixed my signature in the presence of two witnesses.

BOYD B. KEITH.
